(57) **CLAIM**

The ornamental design for a canteen with a screw-on coin slot cap, as shown and described.

DESCRIPTION

FIG. 1 is a perspective view of a canteen with screw-on coin slot cap showing my new design;

FIG. 2 is a top view thereof;

FIG. 3 is a bottom view thereof;

FIG. 4 is a left side view thereof;

FIG. 5 is a right side view thereof;

FIG. 6 is a back elevation view thereof; and,

FIG. 7 is a front elevation view thereof.

The broken lines shown in the drawings represent portions of the canteen with screw on coin slot cap that form no part of the claimed design.

1 Claim, 2 Drawing Sheets
